UNITED STATES PATENT OFFICE.

GRENVILLE M. STEVENS, OF PORTLAND, MAINE.

MACHINE FOR FORMING PULP INTO VESSELS OF VARIOUS KINDS.

SPECIFICATION forming part of Letters Patent No. 320,720, dated June 23, 1885.

Application filed July 9, 1884. (No model.)

To all whom it may concern:

Be it known that I, GRENVILLE M. STEVENS, of Portland, in the county of Cumberland and State of Maine, have invented certain new and useful Improvements in Machines for Forming Pulp into Vessels of Various Kinds; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a top view. Fig. 2 is a side sectional elevation.

Same letters show like parts.

My invention relates to machines for making ware and other such articles of pulp. It employs centrifugal force for the power by which the different vessels are formed.

Any kind of vessel can be made and formed in my invention.

The former or vessel into which the pulp is introduced determines the shape of the article to be formed.

The principle or mode of operation is this: Pulp in a measured quantity, mixed with the proper amount of water, is introduced into the forming vessel or receptacle while said vessel is in a condition of rapid revolution on a vertical axis. The pulp is thus, by the action of centrifugal force, thrown against the inner periphery of the cylinder and formed as the said cylinder is formed—that is, into the desired shape. The water is thrown off through sieves and perforations, as will be hereinafter more especially described, and the pulp thus left comparatively dry, compacted, uniformly placed and deposited, and formed into the vessel sought to be manufactured.

The interior of the "forming-vessel" (as I shall call it in this specification) is furnished, first, with an interior lining of fine wire-netting, then with one of a coarser texture, and then with a series of upright rods a little distance apart. The cylinder itself is perforated with numerous holes sufficient for the escape of the water. The forming-vessel is surrounded by a conical cylinder with the end of the

smaller diameter at the top. This cylinder has scuppers, through which the water escaping from the pulp runs off out of the machine. The perforated cylinder is furnished on the outside with ears. The cylinder is composed of three curved parts, which, when placed together, form the cylinder.

At the top end of my device is a yoke, H, with an aperture, L. This yoke H fits inside of the cylinder, and is made to fit tightly by 50 rubber rings b.

At E are the upper ends of rods passing down through rings F F' F''. These rings have inclined edges to fit against the inclined edges of the ears o on the outside of the perforated cylinder. The upright rods pass down through the rings F, &c., and through the bottom flange, B, of the machine, where they are secured with nuts. The bottom flange supports the whole structure.

The outer perforated cylinder is shown at G, and rests in a recess in the center of the flange B. Next are the rods shown at n. Next is the coarser sieve. (Shown at K.) Next is the finer sieve. (Shown at K'.)

A is the shaft, rigidly connected with the flange B, so as to impart its rotation thereto.

M are the perforations of the cylinder.

I are arms extending from the lower side of the yoke H to a cap, m. Into this cap is fitted 80 the rod p. This rod slides in and out of the sleeve J. The rod p is held at any position by the screw or other device r.

That part of the yoke H surrounding the aperture L may be made capable of being drawn 85 down into the cylinder G, and its distance from the bottom of the cylinder determines the height or length of the vessel to be formed in the cylinder.

I' is a conical bottom filling the bottom end 90 of the cylinder G. To make it tight, it rests upon a rubber packing, b'.

As shown in the drawings, the device is arranged to make a roving-can; but, as before observed, the shape of the interior of the 95 forming-cylinder can be varied to suit the form of the vessel desired to be formed.

When the parts are all put together, and the shaft A caused to revolve rapidly, the pulp and water are introduced at L. The revolution 100

throws the pulp against the interior periphery of the cylinder and against the finer wire sieve K'. The water passes out in the spaces of the sieves, between the rods, through the 5 perforations in the cylinder G, and so escapes through the scuppers D.

When the article is formed, the rods E are unscrewed, the yoke H taken off, and the perforated cylinder, with its rods and sieves, lifted 10 up and taken off the flange B. The cylinder G, being in three parts, is taken apart, the rods removed, and the wire sieves will then spring away from the outside of the formed article, or may be removed. The walls of the 15 formed vessel can then be placed away to dry and mature. The bottoms are then nailed in in the common way, if the article is formed without the pulp bottom. It will be seen that great rapidity in the manufacture is thus se- 20 cured, and uniformity in the character, density, compactness, and thickness of the walls of the vessel made.

No pressure is employed to express the water, as in many machines for the like pur- 25 pose with mine. The divisions of the cylinder G are indicated by the lines t in the top view, Fig. 1.

It will be understood that the outer cylinder, C, may be stationary, while the inner cyl- 30 inder, G, revolves within it and within the rings F, &c. To effect this, the shaft A is splined onto the bottom of the rod J, as seen

at I". In this case the shaft A would turn in its socket in the flange B. When the whole machine, including the outer cylinders, re- 35 volves together, a vacuum is produced around the cylinder G, that both aids in drawing the pulp to proper position and aids in its distribution on the sieve, and also draws off the water from the introduced pulp.

What I claim as my invention, and desire to secure by Letters Patent of the United States, 40 is—

1. The perforated cylinder G, the rods, and the inner and outer sieves of different textures, 45 in combination with the conical bottom I', yoke H, aperture L, and rods J and p, and arms I, the same to be operated as herein set forth.
2. In combination with the inner cylinder, G, and its contained devices, the outer cylinder with scuppers D, and the flange B, as 50 herein set forth.
3. The combination, with the cylinder G, of the movable part of the yoke A, arms I, and rods J and p, to regulate the height of the vessel 55 to be formed, as herein set forth.

In testimony that I claim the foregoing as my own I affix my signature in presence of two witnesses.

GRENVILLE M. STEVENS.
